(57) **CLAIM**

The ornamental design for a pendant, as shown and described.

DESCRIPTION

FIG. 1 is a front view of a pendant showing my new design.

FIG. 2 is a rear view of the pendant.

FIG. 3 is a first side view of the pendant.

FIG. 4 is a second side view of the pendant.

FIG. 5 is a top view of the pendant.

FIG. 6 is a bottom view of the pendant; and,

FIG. 7 is a perspective view of the pendant.

The broken line of FIG. 7, illustrating a necklace is for illustrative purposes only and forms no part of the claimed invention.
